(57) CLAIM

The ornamental design for a dual-sole shoe with red outsole patch, as shown and described.

DESCRIPTION

The file of this patent contains at least one drawing executed in color. Copies of this patent with color drawing(s) will be provided by the Office upon request and payment of the necessary fee.

FIG. 1 is a perspective view of an embodiment of our new design of a dual-sole shoe with red outsole patch, in which the outsole patches are hatched using the USPTO convention of solid vertical lines for red or pink;

FIG. 2 is a first side view of the design of FIG. 1;

FIG. 3 is a second side view of the design of FIG. 1;

FIG. 4 is a top view of the design of FIG. 1;

FIG. 5 is a bottom view of the design of FIG. 1;

FIG. 6 is a front view of the design of FIG. 1;

FIG. 7 is a back view of the design of FIG. 1;

FIG. 8 is a perspective view of another embodiment of our new design of a dual-sole shoe with red outsole patch;

FIG. 9 is a first side view of the design of FIG. 8;

FIG. 10 is a second side view of the design of FIG. 8;

FIG. 11 is a top view of the design of FIG. 8;

FIG. 12 is a bottom view of the design of FIG. 8;

FIG. 13 is a front view of the design of FIG. 8; and,

FIG. 14 is a back view of the design of FIG. 8.

The broken lines illustrating the upper, the half moon patch, the groove, and the heel stripe in the above described depict environment and form no part of the claimed design.
